DESIGN FOR A CAPE.

Design No. **6,631**, dated May 6, 1873

UNITED STATES PATENT OFFICE.

MARTIN LANDENBERGER, JR., OF PHILADELPHIA, PENNSYLVANIA.

DESIGN FOR A CAPE.

Specification forming part of Design No. 6,631, dated May 6, 1873; application filed April 8, 1873.

To all whom it may concern:

Be it known that I, MARTIN LANDENBERGER, Jr., of Philadelphia, Pennsylvania, have invented a Design for a Garment, of which the following is a specification:

The figure in the accompanying drawing clearly represents my design for a cloak or circular.

The hood A has lapels *a a*, a row of buttons, *b*, a bow, *d*, with long pendent ends, and is edged with a narrow gimp-like fringe, *e*, which also extends around the entire outline of the garment, the latter being slashed or split at the bottom, as shown at *f*, and being turned over at its upper edge so as to fit loosely around the wearer's neck, and form lapels *g g* at the front.

Irrespective of colors employed, I claim—

1. The design for a garment with the hood A and the supplementary lapels *g g*, substantially as shown and described.
2. The design for the whole garment, substantially as described, and as represented in and by the accompanying drawing.

In testimony whereof I have signed my name to this specification in the presence of two subscribing witnesses.

MARTIN LANDENBERGER, JR.

Witnesses:

J. J. BUCHEY,
JNO. JAY WARD.
